WILLIAM STEIN, OF CAMDEN, NEW JERSEY.

Letters Patent No. 84,228, dated November 17, 1868.

IMPROVEMENT IN TARGETS.

The Schedule referred to in these Letters Patent and making part of the same.

To all whom it may concern:

Be it known that I, WILLIAM STEIN, of Camden, in the county of Camden, and State of New Jersey, have invented a new and improved Self-Setting Target; and I do hereby declare that the following is a full, clear, and exact description thereof, which will enable those skilled in the art to make and use the same, reference being had to the accompanying drawings, forming part of this specification.

Figure 1 represents a front elevation of my improved target.

Figure 2 is a side elevation, partly in section, of the same.

Figure 3 is a plan or top view, partly in section, of the same.

Similar letters of reference indicate corresponding parts.

The object of this invention is to construct a target, which will produce a constant display of passing objects to the practitioner, said objects or aims being hinged so that they will be turned down when hit, but after being thus turned down, they will be automatically set up before they are again exposed to view.

The invention consists, chiefly, in the use of a disk, frame, or cross, which rotates around a vertical axis, and which supports, near its periphery, or near the ends of its aims, one or more hinged plates, representing animals, or other suitable objects; these plates forming the aims. As the disk or frame is revolved, these aims will, successively, be brought in front of the marksman, and, if he succeeds in hitting one, it will swing on its hinges and be folded down, thus automatically indicating when it is hit.

The invention also consists in the application, in connection with the aforesaid apparatus, of a stationary inclined plate or bar, which serves to automatically set the turned-down plates up again into a vertical position. The turned-down plate, during the revolution of the frame or disk, comes against the said inclined bar or arm, and is, by the same, raised, to be again in position to be hit.

The invention consists, further, in the application, in connection with the foregoing, or an equivalent apparatus, of a screen, through which an aperture is cut or formed, large enough to expose the aforesaid object to be brought to view, as it passes behind the screen during the rotation of its frame or disk. The practitioner, in order to make a successful shot, has to hit the hinged plate or aim as it passes behind and is exposed to view through the aperture of the screen.

The invention, finally, consists in attaching to the support of the rotating frame, behind and in line with the aperture of the screen, another screen, which is to arrest the missiles that pass through the aperture but fail to hit the aims, and to thereby prevent their loss.

A, in the drawing, represents an upright post or frame,

secured upon or in the ground, or on the bed which supports the apparatus.

From its top projects a vertical pin, *a*, which is securely fastened to the frame or post, and around the pin *a* is fitted a tube, *b*, which can freely revolve around the said pin.

On the tube is mounted a pinion, *c*, gearing into a worm, *d*, the axle of which worm has its bearings in lugs projecting from the post or frame *A*.

The axle of the worm *d* is provided with a crank, and can be turned by hand, or other mechanism, thereby, also, revolving the tube *b* and its appendages.

B is a disk or frame, composed, by preference, of a series of radial arms, as in fig. 3. It is firmly secured upon the tube *b*, so as to be revolved with the same.

The manner, herein described, of mounting and revolving the frame or cross *B*, can be varied indefinitely, and does not form part of my invention. I would prefer to have it turned by clock-work, either by the action of weights or springs.

On the end of each arm of the frame *B*, is hinged or pivoted a plate, *C*, representing an animal or other object to be aimed at, and standing, when upright, at right angles to the radius of the disk or frame *B*.

These plates *C*, of which a suitable number can be attached to one frame or disk, *B*, will, when hit from the outside, be swung in, so as to be then in a horizontal position.

D is a bar or plate, projecting from the stationary pin *a*, or from some other stationary device. It is bent, to form an incline, which serves to raise the turned-down plates *C*.

As the frame *B* is turned in the direction of the arrow, in fig. 3, the folded-down plate *C* will be brought against the lowermost part *f* of the incline *D*, which part *f* is low enough to fit under the plate *C*. As the frame continues to revolve, the plate *C* will be gradually raised on the incline until it is again in the upright position.

E is a screen, set up in front of the apparatus hereinbefore described. This screen has an aperture, *g*, through which the upright plates *C* will become successively visible.

F is an upright screen or plate, fitted upon the upper end of the pin *a*, or otherwise arranged stationary on the apparatus, behind and parallel with the screen *E*, and between two diametrically-opposite plates *C*, as is clearly indicated in fig. 3.

This screen *F* is to arrest those missiles that may miss the front plate *C*, to prevent its loss, and its hitting, from the back, the rear plate *C*.

The marksman, with rifle, bow, cross-bow, or other instrument, stands in front of the screen *E*, and aims at the plate *C*, as it becomes visible through the aperture *g*. If he hits the aim, the same will be turned down, and will then be automatically set up again by the in-

cline D, to be in an upright position when it again arrives in rear of the aperture g .

The target will thus produce a continuous display of moving aims, which will automatically indicate when they are hit, without requiring the attendance of a person, to reset them in the proper position after having been turned down.

Having thus described my invention,

What I claim as new, and desire to secure by Letters Patent, is—

1. The swinging plates or aims C C, hinged or pivoted to the rotating frame or disk B, substantially as herein shown and described, to form a target in which the aim will automatically indicate when it is hit, as set forth.

2. The rotating disk or frame B carrying the hinged

or pivoted plates C, in combination with the incline D, for automatically resetting the plates C, substantially as herein shown and described.

3. The screen E, having the aperture g , in combination with the rotating frame B, and with the plate C hinged or pivoted thereto, as set forth.

4. An automatically-adjusting target, consisting of the rotating frame or disk B, of the hinged or pivoted plates or aims C, of the stationary incline D, perforated screen E, and ball-arrester F, all arranged in combination with each other, and made and operating substantially as herein shown and described.

WM. STEIN.
